UNITED STATES PATENT OFFICE.

LOUIS ELIE SEIMBILLE, OF PARIS, FRANCE.

ELECTRIC WATER-HEATER.

1,383,033.

Specification of Letters Patent. Patented June 28, 1921.

Application filed September 24, 1918. Serial No. 255,519.

To all whom it may concern:

Be it known that I, LOUIS ELIE SEIMBILLE, abbot, of 42 Rue du Montparnasse, Paris, France, have invented Electric Water-Heaters, of which the following is a full, clear, and exact description.

This invention relates to electric water heaters and has for its chief object to provide a compact and efficient heater combined with a cock or faucet and adapted to heat running water to any desired temperature within a very short time.

This object, and others, which will be apparent from the following description, are accomplished by arranging in a casing of small cross-section, connected with a water supply pipe, one or more resistance elements adapted to be immersed in the water that is caused to flow through said casing. These resistance elements are preferably in the form of metal wires or strips detachably mounted in the casing, and they are in direct contact with the water to be heated so that the entire amount of the heat generated by passing an electric current through the resistances will be utilized to heat the water. Any suitable metal may be used in said resistance elements, non-oxidable metals being preferable, though rather costly. Very good results have also been obtained with metals which are only slightly oxidizable or are rendered so by applying thereto a galvanoplastic deposit, a thin layer of enamel or any superficial coating adapted to resist the action of current and water. Resistances of nickel-chromium, thus protected, have been subjected to a current of 15 kilowatt hours for more than 300 hours without appreciable deterioration.

The flow of water is controlled by means of a cock or faucet which is operatively connected with a switch adapted to control the supply of current to the resistance elements. The connections are preferably such that the current is switched on as soon as the cock is moved from its inoperative position, and a uniform current is supplied during the further operation of the cock, so that the resulting temperature of the water will be in inverse proportion to its rate of flow, and any desired temperature will be obtained by moving the cock to a predetermined position.

It will be observed that by wholly immersing the resistance elements in the water an electric current of greater intensity may be

sent therethrough than if the resistances were incased, as in most heaters of usual design. This arrangement of the resistances and the use of elements of very small cross-section and a casing of small capacity insure a high efficiency and a remarkable quickness of action in bringing the water to the desired temperature.

Figures 1 to 3 of the accompanying drawing show in vertical sections, by way of example, various embodiments of the invention.

The apparatus shown in Fig. 1 is constituted broadly by a casing *a* in which the transformation of the electrical current into heat is effected. This casing, which may be of any suitable shape, is preferably of earthenware, porcelain, steatite or any other material which is a nonconductor and not attacked by boiling water.

The water under pressure is fed through a pipe *b* which opens into the lower part of the casing *a*, and it flows away at the upper part thereof through a pipe *c*.

The casing *a* contains the resistance *d* fixed and coiled in a spiral on an insulating support *e*. To prevent the resistance from oxidizing or disintegrating it ought to have the least possible number of points of contact with its support *e*. To this end, the support is not constituted by a plain cylinder, but by a column of polygonal or other form presenting sharp edges between which the water can circulate freely and surround the resistance on all sides.

The ends of the resistance *d* are connected to two external terminals *f*, *f'* connected by conductors to the source of current.

The admission of water into the apparatus is regulated by a cock *g* the opening of which to a greater or lesser degree allows the temperature of the water to be graduated at pleasure. The current is sent into the apparatus by a two-pole switch *h* which is preferably connected with the cock *g* in such a way that the operator has only to operate said cock to open a passage simultaneously for the water and for the current, the passage for the current being effected by the contact of the switch *h* with the stationary contacts *i*, *i'*.

As soon as the cock *g* is moved from its closed position the switch *h* is closed and it remains closed during the further operation of the cock as it is gradually brought to the fully open position. Likewise when the cock

- g* is returned to the closed position, the switch *h* is not thrown open until the flow of water has been completely stopped. With this arrangement a uniform current is sent through the resistance whenever the water is running, and whatever be its rate of motion. The amount of heat imparted to the water, consequently, depends solely upon the length of time it remains in contact with the resistance *d*, and the temperature of the water issuing from the casing is inversely proportional to its rate of flow. By suitably operating the cock *g* it thus is possible to heat the water to any desired temperature, the immediate contact between the resistance and the water insuring a practically instantaneous adjustment of the temperature conditions brought about by the operation of the cock.
20. The cock *g* and the switch *h* may be of the form shown or of any other suitable shape. There may be adopted for example, the arrangement which consists in connecting by a Cardan joint the prolonged spindle of the cock to the spindle of an ordinary bipolar commutator.
25. The water which enters the lower part of the casing *a* arrives in the very reduced spaces *j*, *j'* comprised between the walls of the casing and the superheated resistance or resistances *d*; in contact with the resistances the small quantity of water which is contained in the spaces *j*, *j'*, absorbs the whole of the calories produced and escapes through by the pipe *c*; it is replaced at once and without interruption by the ascending column of water, which constantly goes on cooling down the resistances and running away when heated to the desired extent.
30. Fig. 2 shows a modification in which the resistance *d* formed by a non-oxidizable metal wire or ribbon is held freely in a spiral in the casing *a*, instead of being fixed upon a support as in the case of Fig. 1.
35. In the modification shown in Fig. 3, the resistance *d* is carried by an insulating support *e* as light as is possible, and having a helicoidal groove in which the resistances is arranged.
40. The apparatus shown in Figs. 2 and 3 may, of course, be provided with the cock and switch arrangement illustrated in Fig.

1 and their operation is the same as that of the embodiment first described.

In each of the apparatus above described, 55 it is essential that the section of the water delivery tube be greater than that of the cock in order to prevent the water from spouting out of the apparatus under a high pressure.

60. The water is admitted in all cases, into the apparatus at the base of the casing *a* and flows away therefrom at the upper part so that even when at rest, the resistances always remain protected against an abnormal rise of temperature.

65. The apparatus is electrically insulated from the leaden pipes which have to supply it by a pipe of any insulating material such as ebonite, porcelain, caoutchouc, etc., for a 70 distance at least 25 centimeters.

75. The resistances may be of different materials according to the length of life it is desired to insure to the apparatus, and according to the use for which the hot water is intended.

80. It must be quite understood that the forms, materials, dimensions and details of the apparatus may be varied according to requirements, without departing thereby from the principle of the invention as set forth in the appended claim.

I claim:

An electric water heater comprising a narrow elongated casing, a water supply 85 pipe opening into the bottom part of said casing, a valve in said pipe, a discharge spout of larger cross-section than said supply pipe connected to the top part of said casing, and means controlled by said valve 90 for heating the water in said casing to a temperature inversely proportional to the rate of flow of the water, said means including a switch and a coiled resistance element in immediate contact with the water in said 95 casing and wholly immersed therein.

The foregoing specification of my "system for the instantaneous and electrical heating of water" signed by me this 24th day of August, 1918.

LOUIS ELIE SEIMBILLE.
